UNITED STATES PATENT OFFICE.

WINFIELD SCOTT BARAGER, OF HUNT, NEW YORK.

WASHING-MACHINE.

SPECIFICATION forming part of Letters Patent No. 734,154, dated July 21, 1903.

Application filed March 24, 1903. Serial No. 149,347. (No model.)

To all whom it may concern:

Be it known that I, WINFIELD SCOTT BARAGER, a citizen of the United States, residing at Hunt, in the county of Livingston and State 5 of New York, have invented certain new and useful Improvements in Washing-Machines; and I do hereby declare the following to be a full, clear, and exact description of the invention, such as will enable others skilled in 10 the art to which it appertains to make and use the same, reference being had to the accompanying drawings, and to the figures of reference marked thereon, which form a part of this specification.

15 This invention relates to that class of washing-machines in which the water or other liquid is sucked and forced through the clothes by vertically-reciprocating pounders.

The object of the invention is to produce 20 an improved device of that kind characterized by strength and simplicity and ease and effectiveness of operation.

In the accompanying drawings, Figures 1 and 2 are side elevations at right angles, respectively. Fig. 3 is a top plan view.

Referring specifically to the drawings, 6 indicates a central standard having at the bottom a supporting-cone 7. This cone is adapted to rest with its broad base on the clothes 30 in a tub, and its size and shape are such that it affords an adequate support for the machine. Pivoted at its middle to the top of the standard is a rocking beam 8, having at each end the handles 9.

35 A pair of pounders are indicated at 10, preferably kidney-shaped, as shown, so as to substantially surround the central standard, and thus reach clothes all around the same with little turning of the apparatus.

40 The rocking beam and the pounders are

connected by rods 11, which are looped through the beam between the handles and the pivot and have their screw-threaded ends fastened in the top of the lobes of the pounders by nuts, (indicated at 12.) To guide the reciprocation of the rods, they pass through guide-bars 13, which are crossed and firmly fixed to the central standard.

The pounders are hollow, as may be understood, and the tops thereof are curved or 45 dished to give strength.

In operation the clothes to be washed are placed in water under the machine in a tub, and an up-and-down movement is given the pounders by means of the beam, whereby the 50 water is sucked and forced through the clothes and effectively removes dirt therefrom.

What I claim as new, and desire to secure by Letters Patent, is—

1. In a washing-machine, the combination 60 with a standard, and a rocking beam at the top and lobed pounders beside the bottom thereof, of double connecting-rods looped through the beams and joined at their ends to the lobes of the pounders, substantially as 65 described.

2. In a washing-machine, the combination with a standard, and a rocking beam at the top and a pair of pounders at the bottom thereof, of a double connecting-rod looped 70 through the beam and connected at the ends to each pounder, and guides supported by the standard, through which the rods work.

In testimony whereof I affix my signature in presence of two witnesses.

WINFIELD SCOTT BARAGER.
